TAMP RETRACTION DEVICE FOR TAMP TYPE
PACKER

Walter S. Bohlman, Wilmington, Del., assignor to Hercules Powder Company, Wilmington, Del., a corporation of Delaware

Filed May 13, 1957, Ser. No. 658,736

8 Claims. (Cl. 86—20)

This invention relates to an improved tamp type packer. In one aspect, this invention relates to a piston-cylinder assembly particularly advantageously applied in combination with a tamp type packer and associated with fluid pressure sources for moving tamps from the work in response to filling of the containers, and for moving the tamp from the work when the cycle is stalled by failure of the container to fill. In still another aspect, this invention relates to a piston type assembly in combination with a tamp vibratory type packer and associated with a plurality of fluid pressure sources for separating a tamp rod from the work, independently of structure in the said assembly for normally moving the tamp during the regular packing cycle. In still another aspect, this invention relates to a method for operating a tamp vibratory type packer wherein a separate fluid pressure source is utilized in the retraction of a tamp to resume the packing cycle stalled by failure of the tamp to separate from the work.

In the copending application of Walter S. Bohlman and Jack D. Hayes, Jr., Serial No. 346,206, filed April 1, 1953, now abandoned, is disclosed and claimed a packer wherein pulverulent materials are driven from a hopper by action of reciprocating tamp rods through nipples in the hopper floor and allowed to gravitate into containers, the latter being meanwhile maintained in a state of vibration to consolidate the material to a uniformly packed density.

The packer above referred to contains a platen adapted to support, and vibrate and impart vibration to, one or more of the containers to receive solids driven from the hopper. Each tamp rod is connected with a piston in a cylinder-piston assembly contained in a reciprocating crosshead driven by a suitable power source, the associated fluid pressure sources of the assembly maintaining the piston under fluid pressure to hold the tamp rod in an extended or packing position, i.e., in operating position. When the container fills, pulverulent material builds up in the nipple and causes the rod to retract a distance equal to the length of the core formed in the nipple. By the rod's retraction, the piston is forced back within the cylinder an equal distance and finally permits access behind the piston of a fluid pressure higher than the above said fluid pressure to overcome the same and further force back the piston a sufficient distance to separate the tamp rod from the work material. The crosshead is adapted to continuous reciprocation and when the last container is filled and the last rod raised, means is actuated for terminating vibration of the platen, lowering the platen, and moving the filled containers to a separate stage for crimping or further handling as the case may be. Empty containers are then brought to the platen and the cycle is repeated. The entire operation is automatic.

As applied to the packaging of explosives, for economic and other reasons, the container is fabricated from a paper-type material. In some instances the paper container, as a result of the vibration or defects in structure, splits, bulges, breaks or in some other manner fails so that the pulverulent material being fed to it fails to enter or escapes and the container cannot fill. As the machine,

in order to maintain the operating cycle, must await the retraction of the last tamp rod which in turn must await the filling of the last container and the building of a core, the failure of any container not only stalls the operating cycle but also subjects the other containers that are filled to a prolonged state of vibration and, consequently, to a too high density of the packed material.

This invention is concerned with an improved piston-cylinder assembly with means for moving such a laggard tamp rod from a tamp system of the above described type, independently of structure of the said assembly for moving the tamp from the work during the regular packing cycle, in a manner such that the packing operation cycle stalled by the laggard tamp can be resumed without adversely affecting the density of the material in the normally packed containers.

An object of this invention is to provide a tamp-type packer in combination with a device for separating a tamp from the work independently of structure for so separating the tamp during the regular packing cycle. Another object is to provide a piston-cylinder assembly for resuming the normal cycle of a tamp-type vibratory packer above described, which has been stalled by failure of a last tamp rod to retract and actuate the means for continuation of the cycle. Another object is to provide a method for operating a tamp-type packer of the above described type, wherein a laggard tamp which would cause stalling of the packing cycle is caused to retract, to thus continue the cycle, independently of the manner in which the tamp would be retracted during the normal cycle. Another object is to provide a piston-cylinder assembly particularly applicable for retracting one or more of the tamps in a tamp-vibratory packer, independently of structure for that purpose during the regular packing cycle. Other objects and aspects will be apparent in light of the accompanying disclosure and the appended claims.

In accordance with this invention, a piston-cylinder type assembly is provided which is particularly advantageously applied in combination with a tamp vibratory type packer to cause resumption of the normal cycle when stalled during the packing portion of the cycle by failure of a tamp rod to move from the work during the normal cycle, which comprises a fluid-tight cylinder; a piston disposed fluid-tight within said cylinder; a rod in said cylinder connected with an end of the said piston and extending longitudinally from the said piston end and through an end of said cylinder; a first conduit opening into said cylinder at a point in a side thereof so as to be in direct communication with a side of said piston when said piston is moved toward the above said cylinder end to extend said rod from said cylinder, and said piston closing said first conduit when in said direct communication therewith; a second conduit opening into said cylinder at a point in a side thereof intermediate said piston and said cylinder end when said piston closes said first conduit; conduit means in said cylinder connecting said second conduit with said piston end only when said piston closes said first conduit; and a third conduit opening into said cylinder at a point intermediate said first conduit and the end of said cylinder opposite the above described cylinder end.

Further, in accordance with this invention, an improvement is provided in the operation of a tamp-vibratory type packer of the kind above described, wherein tamp rods are each affixed to a piston in a cylinder contained in a reciprocating crosshead and are reciprocated therewith to contact a solid pulverulent material to move said material into a packed position in a container, wherein each said piston is maintained by fluid pressure in said cylinder to support said piston and rod in its working position during the said reciprocation to effect the tamping and each said

piston is moved by force of higher fluid pressure so as to move the said piston and rod away from the working position in response to filling of the container, wherein only after the last tamp rod is moved from said working position, said machine automatically transfers the filled containers, and wherein at least one of said containers fails to fill and the operating cycle of the machine is thereby stalled, the said improvement providing for resumption of said operating cycle when said container fails to fill, which comprises maintaining a source of fluid at said high pressure available for application to the said piston to move same so as to move said rod from said operating position only for a distance sufficient to allow the first said high-pressure air supply to be applied to the said piston, and applying air pressure to said piston from said source when said container fails to fill, thereby engaging the said piston with the original high-pressure fluid source to re-establish the operating cycle of the machine.

The invention is illustrated with reference to the drawings, of which Figure 1 is an enlarged detail of the piston-cylinder assembly of this invention; Figure 2 is an elevational section taken along line 2-2 of Figure 3; Figure 3 is a cross section taken along line 3-3 of Figure 2, including crimping structure not shown in Figure 2; and Figure 4 is a schematic showing illustrative of one form of apparatus by which fluid under pressure can be conveyed to the piston-cylinder assembly of this invention.

With reference to Figure 1, fluid-tight cylinder 48 is closed at its ends 48c and 48d by cylinder heads 48a and 48b. Piston 49 is disposed in cylinder 48 in fluid-tight relation with the cylinder walls and slidably therein by seals 49a and 49b, preferably of the O-ring type. Conduit or port 53 in a side wall of cylinder 48 is connected with conduit 54 and header 55. Rod 44 in cylinder 48 is connected with the end 49c of piston 49 generally axially, and extends longitudinally from the piston end 49c through cylinder head 48a as a tamp rod for a tamp-type packer described hereinafter. Rod 44 is sealed in cylinder head 48a by spaced apart O-ring type seals 74 and 75, or in any other suitable manner. Conduit 54 opens by port 53 in the side of cylinder 48 at a point so as to be in direct communication with a side of piston 49, and to be closed by sealed piston 49, when the said piston is moved toward closure 48a to extend rod 44 to the tamping or working position. In the embodiments shown, port 53 is disposed intermediate the O-ring seals 49a and 49b, for maintaining piston 49 fluid tight in cylinder 48, and is substantially adjacent the O-ring seal 49a. Conduit 71, connected with header 72, opens via port 70, generally through a side wall of cylinder 48, into cylinder head 48a and annulus 76 disposed around rod 44 therein. Port 70, in any event, is spaced from port 53 a distance at least sufficient so that seal 49b is always intermediate ports 53 and 70 when piston 49 is moved, the maximum distance to extend rod 44 from cylinder 48 through cylinder end 48c, the minimum distance in any event being the distance between seals 49a and 49b. Piston 49 in any case does not extend in cylinder 48 to permit seal 49a to move to a point intermediate ports 53 and 70. In the now preferred form, cylinder head 48a is disposed in the cylinder, as shown, as a stop for piston 49 to terminate further extension of piston 49 toward that cylinder end in order to prevent movement of seal 49a past port 53.

The groove 73 extends from the piston end 49c along rod 44 for a distance sufficiently great that it is disposed in direct communication with port 70 as long as piston 49 is in a position to maintain port 53 closed. Most advantageously, the length of groove 73 is that which permits its direct communication with port 70 so long as piston 49 is disposed to close port 53 but such that it terminates its communication with port 70 immediately upon movement of the piston 49 out of direct closing communication with port 53. Thus, groove 73 is preferably of such length that it maintains itself in direct communication with port 70 only so long as piston 49 is

positioned so as to close port 53. Rod seal 75 in cylinder head 48a is disposed intermediate port 70 and the exterior end of head 48a at a point so as always to encompass groove 73.

Conduit 51 connected to manifold 52 opens into a side of cylinder 48 via port 50 which is spaced from port 53 preferably so as to be in close proximity to cylinder head 48b but, in any event, always in direct communication with the interior of cylinder 48. Piston 49 is always so disposed in cylinder 48 with its end 49d in direct communication with port 50. Preferably, closure head 48b acts as a stop for piston 49 to prevent passage of the piston to a point such that its end 49d would be out of direct communication with port 50.

Rod 44a in cylinder 48 is connected with piston 49 at end 49d and extends longitudinally from piston end 49d through cylinder head 48b in sealed relation therewith by O-ring type seal 75a.

An orificed cam member 56, outside cylinder 48, is 20 slidably mounted on an extension 48e of cylinder head 48b and is freely movable longitudinally. It is adapted to be pushed slightly upward and away from cylinder 48 by the end of rod 44a engaging extension 58 when rod 44a is extended from cylinder 48 by movement of piston 25 49 toward closure head 48b. Cam member 56 is adapted to be moved slightly downward toward cylinder 48 by nut 57 on the end of rod 44a when the piston 49 is extended toward closure 48a and substantially in contact therewith.

Near the lower extremity of cam member 56 there is 30 an extended portion 59 which, as cam member 56 is moved toward cylinder 48, engages arm member 60 attached to a rotatable shaft 61 mounted in bearing member 62. Shaft 61 is spring loaded, as illustrated by spring 61a, to rotate clockwise. Such clockwise rotation is 35 limited by engagement of members 60 and 59. Shaft 61 has an attached end lever 63 which, by rotation, engages and actuates valve means 64 for further actuation of the tamp-vibratory machine as described hereinafter.

A device of Figure 1, as illustrated with reference to Figures 2 and 3, is contained with a plurality of similar devices on the crosshead member 47 so that a plurality of tamp rods are operated simultaneously as crosshead assembly 42. As each cam member 56 rises under the influence of piston 49 and rod 44a, its extension 59 clears elongated member 60, thereby releasing some of the force that holds shaft 61 in a stationary position to which it has been rotated counterclockwise against the tension of spring 61a. However, until all piston-cylinder assemblies have operated to remove extensions 59 from contact with elongated members 60, shaft 61 remains stationary. When the extension 59 of the last unit operates to clear and release member 60, the pull of tension of spring 61a rotates shaft 61 clockwise, causing actuation of valve means 64 with resulting termination of vibration of the platen and lowering of the same to continue the cyclic operation.

With reference to Figures 2 and 3, the tamp-vibratory type packer embodying the piston-cylinder assembly of this invention as applied to packing explosives is shown supported by a frame 10. Platen 11 is supported adjacent each end of resilient mountings 12 and can be raised or lowered by means of fluid pressure within cylinders 13. A pneumatic vibrator 15 is attached to the underside of the platen 11 at 14 with the power stroke of the piston 15a being in the vertical direction or normal to the plane of the platen 11. A rack 16 for receiving filled cartridges is rotatably mounted on an axle 17 and is actuated to three positions by pneumatic cylinders not shown. A crimping assembly 19 is shown disposed directly above the rack 16 when rack 16 is in the vertical position shown. The crimping assembly is divided into two sections, 21 and 22. The lower section 22 contains folding dies 23, while the crimping plungers 24 are mounted in the upper section 21 and extend downwardly into dies 23. Piston rods (not shown) lead

from a piston in a pneumatic cylinder (not shown) through the member 21 and are pressed against member 22. The entire crimp assembly 19 is synchronized with the unloading of containers from the platen into the rack so as to be pulled down upon a container in upright rack 16 to make the crimp.

A shuttle 30 is pivotally mounted at each end on arms 31 which are in turn pivotally mounted on a subframe 31a adjustable up and down for different lengths of cartridges. Pneumatic cylinders are advantageously employed to actuate the movement of the shuttle during operation. Cylinder 33 mounted on the arms 31 and connected to clevis 32 at the base of the shuttle 30, by actuation causes the bottom of the shuttle to swing forward and upward to the position shown by the dotted lines 35. Cylinders 34 mounted on the subframe 31a and connected to the clevises 32a on the arms 31, by actuation, cause the arms 31 and the attached shuttle 30 to swing down and back to the position shown by the dotted lines 36.

Containers 37 held in the vertically positioned shuttle 30 are shown with their closed bottoms resting on platen 11. Directly above the shuttle 30 is mounted hopper 38, the bottom of which is formed by a nipple plate 39. The nipples 40 enter into the mouths of the shells-containers 37 when the shuttle and the platen have each been raised to filling position, the shuttle having been raised prior to rise of the platen. Tandem stirrers 41 are mounted in the hopper 38 on each side of the nipples 40. Crosshead assembly 42 is disposed above the hopper 38 and is reciprocated in its entirety by cranks 43 connecting rods 43a and rods 43b connected through shaft 43c to the power source. Contained in the crosshead assembly 42 are a plurality of piston-cylinder assemblies of Figure 1 described hereinabove. Each rod 44 serves as a tamp rod operating in hopper 38 and is advantageously connected with a wood rod 45, in the packaging of explosives, so that the interior of hopper 38 is free from the presence of metals, except for the nipple plate 39.

The machine of Figures 1 through 3 operates as follows. The explosive material to be packed is introduced uniformly to the hopper 38 by suitable conveyor means 38a. The shuttle 30, while in the dotted position 36, is initially loaded with empty shells by means not shown. The shells are loosely held in the shuttle and are free to move longitudinally therein. Through retraction of the rod of pneumatic cylinder 33 and the extension of the rods of pneumatic cylinders 34, the shuttle 30 is raised to a vertical position so that the shells 37 rest upon the platen 11. Then, through the extension of the rods of cylinders 13, the platen 11 is raised sufficiently to push the shells 37 up within the confines of the shuttle 30 until their open ends embrace the nipples 40 in plate 39 that forms the bottom of hopper 38. Meanwhile, the stirrers 41 are continuously rotating and the crosshead assembly 42 is reciprocating vertically with the tamps 44 attached to elements 45-46 directly above the nipples 40. The tamps being in their shortened position, the tamp tip 46 very nearly touches the powder in the hopper when at the end of its downward stroke. As soon as the raised shells 37 embrace the nipples 40, the vibrator 15 is automatically started and the tamps are extended so that the stroke of the tamp tip 46 extends from above the powder down through the nipples 40, but no further. The sticks 45, with tips 46 continuously reciprocating with the crosshead, force the explosive through the nipples 40 and into the containers where it is continuously consolidated by the vibration imparted to the shells 37 by the vibrating platen 11. Due to uniform introduction of the composition into the hopper 38, the synchronous distribution by stirrers 41, and the reciprocating action of the rods 44 and 45, the shells are filled practically simultaneously, thus exposing the explosive in each shell to practically the same amount of vibration. When the level of consolidated

powder rises above the egress orifice of the nipples 40, the powder is then consolidated in the nipples 40 by tamping action of the sticks 45. All this time, low pressure air is being introduced into the upper part of the cylinders 48 through the port 50. The pressure of this air is such that with each succeeding increment of powder that is packed in the nipples 40, the effective stroke of the rod 44 is shortened by compression of air in the upper part of the cylinder 48 by the piston 49. On the up-stroke of the crosshead assembly, however, the low pressure air again fully lengthens the stroke of the stick 45 and the next increment of powder packed in the nipple by the succeeding stroke is packed to a density sufficient to still further shorten the effective stroke of the stick 45. When each nipple is filled to the desired level, the piston 49 is raised by action of the powder packed in the nipple to a point where seal 49b passes port 53 and allows high pressure air to flow from header 55 into the lower part of cylinder 48. High pressure air from port 53 then overcomes the low pressure air and the piston 49 is then forced into the upper portion of the cylinder 48 to withdraw the stick 45 from contact with the powder in the nipple or hopper. As the high pressure air forces each rod 44 to its upper limit of travel, each cam 56 is lifted and successively clears the lever 60. When the last rod 44 rises and the last cam 56 clears the lever 60, the spring loaded rod 61 is allowed to rotate clockwise to actuate a valving mechanism 64 which shuts off the flow of air to the vibrator 15 and reverses the air in cylinders 13 to lower the platen 11. Lowering of the platen 11 allows the shells 37 to fall away from the nipples 40, whereupon the consolidated, continuous column of powder in the shell breaks away from the nipples which remain sealed by the cores packed therein.

Cylinder 33 is now actuated to swing the bottom of the shuttle 30 and shells 37 outwardly to clear the platen as shown by the dotted lines at 35. The loaded shells, loosely held by the shuttle 30, fall through the shuttle 30 into the rack 16. Cylinders 34 are then automatically actuated to swing down the now empty shuttle 30 to the horizontal position shown by the dotted lines 36. A new group of empty shells is then inserted automatically into the shuttle 30 by an automatic shell feeding device (not shown). The cylinders 33 and 34 are then actuated to raise the shuttle 30 back into the vertical position under the nipples 40. The platen 11 is then raised to engage the new shells with the nipples 40. At this point, the high pressure air in the cylinder 48 from port 53 is drained off to release the pressure below the piston 49. The low pressure air then forces each piston 49 down to extend the rods 44 to their full length below the crosshead. As the rods 44 are forced to their longest effective length, the nuts 57 force the cam 56 downward and the lever 60 is again depressed. The rod 61 is rotated counterclockwise, the valving mechanism 64 is reversed and is cocked or loaded for the next cycle.

The crosshead assembly 42 has continuously reciprocated during this time and with the first stroke of the extended rods 44 and sticks 45, the cores which were built up in the nipples 40 are pushed into the empty shells and the loading and packing operation is repeated. In order to break the core, the initial stroke is under higher air pressure than during the normal tamping operation. Associated structure for effecting the initially high pressure stroke is not shown. During the loading of this group of shells, the rack 16 which contains the loaded first group of shells is swung to the vertical position shown in Figure 3, and the crimping mechanism 19 is pulled downward, by pneumatic valve-cylinder assemblies not shown. As the folding dies 23 turn the edges of the mouths of the shells inwardly, the member 22 maintained apart from the member 21 by means not shown is stopped by means not shown, but 21 continues downwardly forcing the crimping plungers 24 down-

wardly through the folding dies 23 to complete the crimping operation. The pressure is then reversed by cylinder mechanism (not shown) and the crimping assembly 19 is raised to its inactive position. The rack 16 is then forced outwardly by cylinder means (not shown) to the dotted discharging position 58. The finished cartridges are discharged to a waiting tray or moving belt as may be desired.

Except for supplying the material to be packed to the hopper or to a feeding belt and for supplying empty containers to the hopper of the shell feeding machine, the entire operation of the machine shown in Figures 1-3 is automatic. The valving mechanisms employed for this particular machine are operated by air pressure and are assembled from conventional components known to the art. Hydraulic cylinders or equivalent mechanical elements which will effect the necessary movement of the various parts of the apparatus may be substituted, if desired.

As the last tamp goes up and the correspondingly last cam member 56 and its extension 59 clears elongated member 60, the tension on spring 61a causes shaft 61 to rotate clockwise to initiate the next automatic action of the machine.

In the operation of the machine, the vibration imparted to the shell, particularly a shell of irregular construction, during packing, together with resulting movement of the shell sometimes causes the shell to rupture, bulge, break or in some other manner fail to the extent that the shell either fails to fill or fills only after an unduly long packing period, pulverulent material in some events being lost from the system. The failure of the shell to fill, of course, precludes a build up of core in the nipple, and, accordingly, the tamp rod associated therewith fails to rise to open the high pressure air conduit to the bottom of the piston, i.e., via port 53, to raise it out of the tamping operation. So long as the piston fails to rise, of course, the arm 60 is retained by the particular element 59 in the unreleased position against the tension of spring 61a and the platen is thereby retained in raised position in a vibrating state and materials in the shells already filled, are packed to an excessive density. Further, the packing cycle is interrupted and cannot be resumed so that the automatic operation of the machine is stalled.

When a shell fails to fill and thereby stalls the operating cycle, the cycle is quickly resumed by introducing air under pressure into that cylinder 48 by way of conduit 71 through port 70, annulus 76, and groove 73. So long as piston 49 is in a position to close port 53, groove 73 is in communication with annulus 76 and, therefore, communicates high pressure air from port 70 to the end 49c of piston 49, thereby lifting piston 49. Seal 75 is spaced from annulus so as to always encompass groove 73. Groove 73 extends beyond annulus 76 toward seal 75 in cylinder head 48a a distance preferably equal at least to the length of piston 49 and in any event equal to the distance between seals 49a and 49b when piston 49 closes port 53 and is moved a maximum distance to extend rod 44 from cylinder 48. Thus, when by high pressure air from conduit 71, the laggard piston 49 has been raised by a distance equal at least to the distance between port 53 and seal 49b, or further if desired, groove 73 is raised out of communication with air pressure in port 70 and piston 49 is then subject to fluid pressure from port 53, the O-ring seals 49b having been raised to above port 53. Once piston 49 is raised into operative contact with fluid pressure from port 53 or at a predetermined time thereafter as determined by the selected length of groove 73, the rod 44 is raised consonant with the normal operating cycle and the cycle is resumed. Upon rise of the last tamp rod, the vibration of the platen is terminated, it is lowered, and the filled shells are moved on to the crimping step for crimping and further handling.

With reference to Figure 4 is illustrated one embodiment of a fluid pressure system of this invention for ad-

mitting high pressure fluid into cylinder 48 via ports 53 and 70.

Referring to Figure 4, fluid under pressure, which ordinarily, is air, is withdrawn from low pressure source 5 at 80 at a pressure say of about 30 p.s.i.g. and passed via line 81 to header 52 of Figure 1 to maintain low pressure air supply to cylinder 48. Air is withdrawn from high pressure air source 82 via line 83, normally open valve assembly 84, and line 86 at a pressure higher than that of air in line 81, at a pressure in the order of about 60 p.s.i.g., and is passed to header 55 of Figure 1 to maintain high pressure air available for raising piston 49 as described hereinabove.

Valve assembly 84 contains any suitable normally open, three-way valve associated with control means for holding it closed for a short time interval when it is desired to terminate high pressure air flow to cylinder 48 so as to permit piston 49 to descend in cylinder 48. The valve in unit 84 being of the three-way type is adapted to permit air displaced from cylinder 48 by the descending piston 49 to exhaust from header 55 and line 86, via line 87. The control means of unit 84 is preferably actuated to close the valve associated therewith in response to rise of platen 11 to engage empty shells 37 with nipples 40 in plate 39 (Figures 2 and 3). Thus, once the shells 37 are in place and in a state of vibration, valve 84 is caused to close, and to permit high pressure air to be exhausted from cylinder 48 as above described so as to permit piston 49 to descend. The valve in unit 84 is adapted, in conjunction with the timing means associated therewith, to resume its normally open position after piston 49 is in position to close port 53 so that high pressure air is available for raising piston 49 in response to core buildup in nipples 40.

Air under pressure the same as that in line 86 and to be made available in header 72 for injection into cylinder 48 through the groove and annulus structure associated therewith, can be introduced into header 72 by way of line 88 and manually controlled valve 89 via line 91. Thus, the operator, when observing that a cartridge is for some reason unable to fill and noting that all other cartridges have filled and that further vibration will be likely to cause undesirable packing of the explosive, manually holds valve 89 open long enough to permit high pressure air to enter header 72 and raise the piston 49 by way of groove 73 so as to resume the packing cycle.

High pressure air, when desired, can be passed to header 72 automatically by way of lines 83, 86, 94 and 91 via the normally closed timed valve assembly comprising elements 90 and 92 disposed in line 94.

Assembly 90-92 comprises any suitable time valve arrangement. It contains a three-way type valve 92 so that air from lines 83 and 86 can be passed through lines 94 and 91 and so also that air exhausted from cylinder 48 after the piston 49 descends past port 53 can be vented by way of header 72 and lines 91 and 95.

Air under pressure from lines 83, 86 and 88 provides timer-unit 90 with air for the actuation of valve 92. The timer device of timer-unit 90 is set to cause opening of valve 92 to permit delivery of air to header 72. However, the timer device is set to actuate the valve 92 only after a sufficient time has passed for the normal packing of all cartridges. The time interval after which valve 92 is caused to open is that which not only allows normal time for filling of all cartridges but also includes an extra time period to permit the laggard tamp to rise, if at all possible for it to do so before there has been an unduly large amount of vibration to effect undesirable packing density in the cartridge. Once air is passed through valve 92 from line 94 and the laggard tamp has thereby been raised, the normal cycle is resumed. When there are no laggard tamps, timer-unit 90 times out and valve 92 opens after all tamps are up but such action has no effect on the normal cycle, and the next time valve

84 is closed, timer-unit 90 is reset and valve 92 is closed. Any other suitable arrangement for delivery of fluid under pressure to cylinder 48 can be employed as desired, the foregoing with reference to Figure 4 being by way of illustration only.

It is to be understood that the cylinder 48 can be closed by any suitable means, although cylinder heads 48a and 48b extending into cylinder 48 are now preferred. One such alternative is a cap at each end 48c and 48d of cylinder 48 with any suitable means for communicating fluid pressure from port 70 to the bottom 49c of piston 49. In one such embodiment, a closure member in cylinder 48 can be inserted intermediate port 70 and end 48c and containing a conduit in direct communication with port 70 and groove 73 when piston 49 is positioned so as to close port 53.

As will be evident to those skilled in the art, various modifications can be made or followed, in the light of the foregoing disclosure and discussion, without departing from the spirit or scope of the disclosure or from the scope of the claims.

What I claim and desire to protect by Letters Patent is:

1. Apparatus comprising a closed cylinder; a piston disposed fluid tight in said cylinder; a rod in said cylinder connected with an end of said piston and extending longitudinally from said piston end through a first end of said cylinder; a first conduit opening into said cylinder at a point in a side thereof so as to be in direct communication with a side of said piston when the said piston is moved toward said first cylinder end to extend said rod from said cylinder, and said piston closing said first conduit when in said direct communication therewith; a second conduit opening into said cylinder at a point in a side thereof intermediate said piston and said first cylinder end when said piston closes said first conduit; a groove extending along a side of said piston rod in direct closed communication with said piston end, and in direct closed communication with said second conduit so long as said piston closes said first conduit; and a third conduit opening into said cylinder at a point intermediate said first conduit and a second end of said cylinder.

2. In apparatus of claim 1, a first and a second cylinder head respectively in said first and second cylinder ends, as closure means for said cylinder; said third conduit opening into said cylinder at a point in close proximity to said second cylinder head and said second conduit opening into said cylinder at a point in direct contact with said first cylinder head; means for sealing said rod at separate points in said first cylinder head; an annulus formed in said first cylinder head around said rod intermediate said separate points; a passageway connecting said annulus with said second conduit; and said groove being disposed to extend beyond said annulus toward the said first cylinder end for a distance so as to be in said direct closed communication with said second conduit so long as said piston closes said first conduit.

3. In a packing machine of the tamp type in combination with a reciprocable crosshead assembly, a fluid tight cylinder connected with said crosshead with its axis extending in the direction of reciprocation of said crosshead; a piston disposed fluid tight in said cylinder; a rod in said cylinder connected with an end of said piston and extending longitudinally from said piston through a first end of said cylinder, as a tamp rod for said packer; a first conduit opening into said cylinder at a point in a side thereof so as to be in direct communication with a side of said piston when said piston is moved toward said first cylinder end to extend said rod from said cylinder, and said piston closing said first conduit when in said direct communication therewith; a second conduit opening into said cylinder at a point in a side thereof intermediate said piston and said first cylinder end when said piston closes said first conduit; conduit means

in said cylinder connecting said second conduit with said piston end only when said piston closes said first conduit; and a third conduit opening into said cylinder at a point intermediate said first conduit and a second end of said cylinder.

4. In a packing machine of claim 3 said conduit means in said cylinder comprising a groove extending along a side of said piston rod in direct closed communication with the said end of said piston, and in direct closed communication with the said second conduit so long as said piston closes said first conduit.

5. In a packing machine of claim 3 a first and second cylinder head respectively in the said first and second ends of said cylinder, as closure means for said cylinder; said third conduit opening into said cylinder at a point in close proximity to said second cylinder head and said second conduit opening into said cylinder at a point in direct contact with said first cylinder head; means for sealing said rod at separate points in said first cylinder head; said conduit means comprising an annulus formed in said first cylinder head around said rod intermediate the above said separate points, a passageway connecting said annulus with said second conduit, and a groove disposed in the side of said rod and extending longitudinally from said piston; and said groove being disposed to extend beyond said annulus toward the said first end of said cylinder for a distance so as to be in direct communication with said second conduit so long as said piston closes said first conduit.

6. In a packing machine of the tamp type in combination with a reciprocable crosshead assembly, a plurality of fluid-tight cylinders connected with said crosshead, said cylinders having their axes extending in the direction of reciprocation of said crosshead and adapted thereby to reciprocate with said crosshead; a piston disposed fluid-tight in each said cylinder and a rod in each said cylinder connected with an end of said piston and extending longitudinally from said piston downwardly through a first end of said cylinder as a tamp rod for said packing machine; a hopper beneath said plurality of fluid-tight cylinders, and a plurality of nipples in the bottom of said hopper extending downwardly therethrough; each said nipple being in direct alignment with one of said tamp rods, and said hopper being spaced from said plurality of cylinders so that each said tamp rod, when at its downwardmost point of travel during reciprocation, extends into said hopper and through, but not substantially beyond, the bottom end of one of the said nipples to thereby tamp pulverulent materials from said hopper through said nipple; a first conduit opening into each of said cylinders at a point in a side thereof so as to be in direct communication with a side of the piston therein when it is moved toward said first cylinder end to extend said tamp rod from said cylinder, and said piston closing said first conduit when in said direct communication therewith; a first cylinder head in the said first end of said cylinder, and a second cylinder head in a second end of said cylinder, as closure means for said cylinder; a second conduit opening into each of said cylinders at a point in a side thereof in direct contact with said first cylinder head, and a third conduit opening into each of said cylinders at a point intermediate said first conduit and said second cylinder head and in close proximity to said second cylinder head; means for sealing said rod at separate points in said first cylinder head; an annulus formed in said first cylinder head around said rod intermediate the above said separate points; a passageway connecting said annulus with said second conduit; a groove disposed in the side of said rod and extending longitudinally from said piston, and said groove being disposed to extend beyond said annulus toward the said first end of said cylinder for a distance so as to be in direct communication with said second conduit so long as said piston closes said first conduit; a low pressure fluid conduit connected

75 with each said third conduit for conveying fluid under

pressure to said third conduit; a first high pressure fluid conduit connected with each said first conduit for conveying fluid to said first conduit under pressure greater than that in said low pressure conduit; a second high pressure conduit for conveying fluid at a pressure about the same as that in said first high pressure conduit, to said second conduit; a valve in said first high pressure conduit, maintained open, but adapted to be closed in response to expiration of a predetermined duration after rise of the last of said tamps from said working contact, and thereafter to be opened; and a valve in said second high pressure conduit, maintained closed, but adapted to be opened to permit communication of fluid pressure therein to said second conduit.

7. Apparatus of claim 6 wherein said valve in said second high pressure conduit is a manually controlled valve.

8. Apparatus of claim 6 wherein said valve in said second high pressure fluid conduit is maintained closed and is adapted to be opened in response to actuation of a timer device at the end of a predetermined period after the last tamp is to have been removed from the said working contact.
